SHAMPOO BOARD

Filed Oct. 5, 1931

Inventor
H. Lalie

By her Attorney J. Federmann

UNITED STATES PATENT OFFICE

HELEN LALIE, OF BROOKLYN, NEW YORK

SHAMPOO BOARD

Application filed October 5, 1931. Serial No. 566,829.

The main object of this invention is to provide a sanitary shampoo board adapted to be mounted on a table or other horizontal surface adjacent to which a person having his hair shampooed sits, the device being so constructed and mounted that the water and suds drained from the hair will be captured by the board and drained into a suitable basin or container situated at or near the floor.

Another object of the invention is the provision of a device of the class described with an adjustable drain board supported upon a portable base, the angle of the board with respect to the horizontal being variable to suit the immediate requirements.

Still another object is to provide such a device with a plurality of separable component parts, so that the device may be readily cleaned and sterilized.

The above and other objects will become apparent in the description below, in which like-named parts are indicated by like-named characters of reference.

Referring briefly to the drawing, Fig. 1 is a side elevational view of the device.

Fig. 2 is a front elevational view of the device, with the drain board cut away to illustrate the support arms of the adjustable member.

Fig. 3 is a perspective view of the drain board.

Fig. 4 is a perspective view of the rotatably adjustable member in inverse position.

Fig. 5 is a plan view of the assembled device.

Referring in detail to the drawing, the numeral 10 represents a base in the form of an inverted funnel provided with a neck 11. A second funnel-like member 12, whose neck 13 rests within the neck 11, is supported upon the base 10. The plane of the upper periphery of the funnel 12 is tilted rearward, instead of being horizontal, so that any flat surface supported thereon will also tilt rearward.

Within the walls of the upper funnel-like member 12, a hollow hemispherical body 14 is seated, with its surface in contact with the inner walls of the member 12, so that by simple rotation the relative position of this body may be varied. Integral with, and pro-

jecting from diametrically opposite sides of, this body, are resilient arms 15 having turned-in tongues 16 at the extremities thereof.

The drain board comprises as a sheet of flexible material 17 slightly bent to provide a slightly curved channel between its sides, and the latter are turned back toward the center of the board to provide guide walls to constrain liquid flowing along the board to said board. The front end of the board is provided with a semi-circular cut-out 19, from the periphery of which a similarly-curved wall or collar 20 rises, the latter being provided with a rounded or rolled edge 21.

The board 17 is slipped over the body 14 between the fingers or tongues 16 of the resilient arms 15, in doing which the arms are first flexed backward to enable the board to pass between the tongues 16, and upon release of the arms, the tongues securely hold the board on the body by means of the engagement between the tongues and the side walls 18 of the body, as shown in Fig. 2. With the board adjusted so that the arms 15 are at about the middle of the length of the board, the body 14 is inserted into the funnel 12. It is now obvious that, since the board is supported by the body 14, and the latter contacts only with the walls of the funnel 12, the angular position of the board 17 may be varied by merely rotating the body 14. The limit of such variation occurs upon contact of the board 17 with the edge of the funnel 12, but the amount of adjustability between such opposite limits is sufficient for the purpose of the invention.

In use, with the person being shampooed being seated with his back to the table, and the shampooer working from in front of the person, as is the common practice, the device is mounted on the table with the collar 19 set against the upper part of the neck of the person, just below the hair line, and the head is bent back slightly against said collar. As people of various heights are thus treated, the adjustability of the level of the board as described enables the operator to make the necessary adjustment to bring the collar into the position mentioned on the person what-

ever his height within normal limits. While the operation is being performed, the water and suds constantly draining off the hair are captured on the board after passing down the collar 20, and because of the tilt of the board they pass down the same and off into a suitable receptacle which may be placed on the floor.

The use of this device obviates the necessity of the person being shampooed from having to bend over the wash basin, as is usually required, and makes it simple for the operator to work in the person's home.

Obvious modifications in form and construction may be made without departing from the spirit and scope of the invention.

I claim:

A device of the class described comprising a base, a hollow support mounted on said base and having its upper side open to provide a socket, a curved body rotatably mounted in said socket and having diametrically opposed arms rigid therewith, said upper side having a peripheral edge, the plane passing through said edge lying at an angle to the horizontal, a board adapted to rest on said arms, and tongues on the ends of said arms gripping the edges of said board.

In testimony whereof I affix my signature.
